UNITED STATES PATENT OFFICE

MICHAEL J. FARRELL AND LALLY STAFFARONI, OF SCRANTON, PENNSYLVANIA

RAILROAD CROSSING GATE

Application filed January 29, 1931. Serial No. 512,166.

This invention relates to new and useful improvement in grade crossing gates, and more particularly to a gate which will be automatic in operation.

5 The principal object of this invention is to provide an automatic block operated gate for railroad crossings.

Still another important object of the invention is to provide a railroad grade crossing gate wherein means are provided for preventing the trapping of vehicles on the tracks, and to prevent injury to vehicles should the gate descend upon a vehicle.

10 These and numerous other important objects and advantages of the invention will become apparent to the reader of the following specification and claims.

In the drawings:—

Figure 1 represents a side elevational view 25 of the novel gate structure, one of which is located at each side of the track crossing.

Fig. 2 represents a top plan view of the gate structure shown in Fig. 1, with the signals removed.

Fig. 3 represents a vertical sectional view through one post and through one of the swingable sections of the gate shown in Fig. 1.

Fig. 4 represents a horizontal sectional view taken substantially on the line 5—5 of Fig. 3.

Fig. 5 represents a vertical sectional view through one of the gate posts to show the switch devices.

Fig. 6 represents a fragmentary detailed sectional view of the signal post type of gate, the same being a modification of the form of the invention shown in Fig. 1.

Fig. 7 represents a perspective view of the signal box shown in Fig. 1.

Fig. 8 represents a horizontal sectional view looking downwardly, and showing the drive means for the gates at both sides of the crossing.

Fig. 9 represents a horizontal sectional view looking downwardly, and showing the drive means for the gates at both sides of the crossing, and showing individual motors for the several posts of the gates.

50 Referring to the drawings wherein like

numerals designate like parts, it can be seen in Fig. 1, that the double type or dual post type gate shown in Fig. 3, includes the hollow posts 5—5, suitably supported in concrete recess 6. Within each of these posts 5 and journaled through bearings 7—7 is the screw shaft 8. The lower end of each of these screw shafts is provided with a bevelled gear 9. In the form of drive means shown in Fig. 8, a shaft 10 connects the screws 8 by way of the bevel gears 11, at one side of the crossing while a shaft 12 connects the screws 8 on the posts at the opposite side of the crossing by way of the bevel gears 13.

The shafts 10 and 12 are connected together by sprocket and chain connections 14, and an electric motor 15 is employed for driving the shaft 10 directly and through the chain connection 14, the shaft 12 is driven in unison.

In Fig. 9, the bevelled gears 9 of the screw 70 shafts 8 are in mesh with beveled gears 16 which are located on armature shafts of independent motors 17. Each of the shafts 8 is driven by an independent electric motor 17.

Now referring again to Fig. 3, it can be 75 seen (refer also to Fig. 1) that each of the posts 5 has a gate section 18 carried thereby. A pair of followers 19—19 are feedable on the shaft 8 and the gate section 18 is swingably connected to the followers 19—19 by the 80 hinged connections 20, which permits the gate section to swing only in an outward direction. Thus a vehicle trapped between the gates and the opposite side of the crossing can travel through the gates, yet no vehicle can pass through the gates from the approach sides thereof.

The gate section 18 includes a rectangular frame on which is supported the electric bell 21 and suitable fabrications 22. A pair of 90 normally closed switches 23—23 are located on each gate section 18 and as is clearly shown in Fig. 3, a U-shaped member 24 depends from the gate section and carries a resilient buffer 25, on the lower portion thereof.

The upper end portions of the U-shaped member are slidably disposed thru the lower rail of the gate section 18 and are maintained in a position by the spring 25 disengaged from the switches 23—23. Obviously, 100

should the gate descend upon a vehicle, the end portions of the U-shaped member 24 will rise upwardly and open the switches 23-23. This will cut off the motor current supply, stopping the driving motor or motors, so that the vehicle will have an opportunity to proceed without being further injured or damaged by the gate.

As is shown in Fig. 3, in the event a crossing has pedestrian walks, a barrier 26 is provided for each walk. The barrier includes a rectangular-shaped frame from which the legs 27-27 extend. These legs are provided with threaded openings, through which the shaft 8 extends and with openings 28 through which the web 28 extends.

As is apparent in Fig. 3, one side of the post 5 is provided with a slot 30 while the other opposite side of the post is provided with a slot 31. Within the slots are arranged the endless webs 29, the web in the slot 30 being secured at its outside portion to the barrier 26, while the other web in the slot 31 is secured at its outside portion to the gate section 18.

Obviously, these webs serve to prevent rain and snow from entering the interior of the post, thus protecting the working parts of the gate from rust and other deteriorating conditions. As is shown in Fig. 1, a bar 32 bridges the posts of each gate structure and suspended from this bar 32 is the signal unit generally referred to by numeral 33. This signal unit is divided into two compartments, the upper compartment being provided with lenses of a red color, and the lower lenses of the lower compartment being of green color.

Motor reversing switches 34 and 35 are located within the upper and lower ends of the post 5, for engagement by the upper and lowermost followers 19. The switches are located in boxes 36 having suitable closures through which access may be had to the switches. Another box 37 at the lower end of each post, houses a switch 38 which is to be employed when a train stops within the block for the purpose of unloading or for other operations, when it is not necessary that the gate section be down.

Fig. 6 shows a slightly modified form of the invention, wherein one post of each gate is eliminated, and an additional section 18' is hingedly connected as at 19' to the first section 18. The supplemental section 18' which is entirely supported by the first section 18, also carries a pair of switches similar to switches 23-23 of Fig. 4 and the U-shaped actuator 24.

A "Stop" sign 39 is located on the fabrication 22 of both the type of gate shown in Fig. 1, and the type of gate shown in Fig. 6.

The foregoing specification sets forth the invention in specific terms, it is to be understood that numerous changes in the shape, size and materials may be resorted to with-

out departing from the spirit and scope of the invention as claimed hereinafter.

Having thus described our invention, what we claim as new is:

1. A railroad grade crossing gate comprising a post, a gate structure, said post being provided with a slot in one side thereof, said gate being adapted to project through the slot and into the post, means within the post for lifting and lowering the said gate, rollers at the upper and lower ends of the posts within the said slot, and endless web trained over the said rollers, one part of the said web being secured to the gate. 70 75

2. In combination, an elevating gate, a depending U-shaped member, springs on the leg portions of the U-shaped member for maintaining the U-shaped member extended downwardly, and a switch on the gate operated by one leg of the U-shaped member when the U-shaped member is forced upwardly against the tension of the spring. 80 85

3. A railroad grade crossing gate comprising a hollow post, a gate structure, said post being provided with a slot in one side thereof, means within the post for lifting and lowering the said gate, a connection through the slot between the said means and the gate, a vertically disposed endless web operating in the slot longitudinally thereof, said web being secured to the gate to travel therewith. 90 95

In testimony whereof we affix our signatures.

MICHAEL J. FARRELL.
LALLY STAFFARONI.
